Primary Examiner — George D. Kirschbaum*Assistant Examiner* — Richard Kearney(74) *Attorney, Agent, or Firm* — Ohlant, Greeley, Ruggiero & Perle, L.L.P.(57) **CLAIM**

The ornamental design for a finger ring, as shown and described.

DESCRIPTION

FIG. 4.1 is a top side perspective view of a finger ring according to the present disclosure;

FIG. 4.2 is a bottom view thereof;

FIG. 4.3 is a first side view thereof;

FIG. 4.4 is a second side view thereof opposite the first side;

FIG. 4.5 is a top view thereof;

FIG. 4.6 is a front view thereof; and

FIG. 4.7 is a rear view thereof.

The features in broken lines of the figures are included to show portions of the finger ring that form no part of the claimed design.

1 Claim, 7 Drawing Sheets(56)
